UNITED STATES PATENT OFFICE.

WILLIAM DEMUTH, OF NEW YORK, N. Y.

DESIGN FOR A PIPE MOUTH-PIECE.

SPECIFICATION forming part of Design No. 13,050, dated July 18, 1882.

Application filed May 24, 1882. Term of patent 7 years.

To all whom it may concern:

Be it known that I, WILLIAM DEMUTH, a citizen of the United States, residing at New York, in the county and State of New York, have invented and produced a new and original Design for the Mouth-Piece of a Smoking-Pipe, of which the following is a specification.

This design consists in the combination, with a mouth-piece, of a beaded fillet and a series of cavettos, fillets, and ovolos, as hereinafter described.

The accompanying drawing represents a side view of my design.

In this drawing, the letter A designates the mouth-piece, which is provided with a hexagonal flange, a, beneath which is a cavetto, b, a fillet, c, an ovolو, d, a concave colareno, e, an ovolو, f, a beaded fillet, g, an ovolو, h, a cavetto, i, an ovolو, j, and a fillet, k. The fea-

tures described and shown impart to the mouth-piece a novel and ornamental appearance.

What I claim as new, and desire to secure by Letters Patent, is—

The design for the mouth-piece of a smoking-pipe, consisting of the curved mouth-piece A, the hexagonal flange a, the cavetto b, the fillet c, the ovolو d, the concave colareno e, the ovolو f, the beaded fillet g, the ovolو h, the cavetto i, the ovolو j, and the fillet k, as shown and described.

In testimony whereof I have hereunto set my hand and seal in the presence of two subscribing witnesses.

WM. DEMUTH. [L. S.]
